UNITED STATES PATENT OFFICE.

HERMANN FÖTTINGER, OF BERLIN-WILMERSDORF, GERMANY.

INTERNAL-COMBUSTION PUMP.

Application filed September 7, 1928, Serial No. 304,569, and in Germany October 21, 1920.

This application is a continuation in part of, my prior and co-pending application Serial No. 510,879, filed October 27, 1921.

The invention relates to the production of power by the use of a gaseous explosive mixture. Instead of utilizing the force of the explosion to reciprocate a piston, as in the ordinary type of internal combustion engine, I utilize said force to impart increased energy to a liquid moving as an annular body in a stationary cylinder by its kinetic energy and without the use of any rotor.

In carrying out my invention I deliver a stream of liquid in a generally tangential direction to a substantially cylindrical vessel and with sufficient velocity to cause the liquid to form an annular body against the peripheral wall of the vessel, and around a central open space. By controlling the admission 20 and escape of this rotating body and the pressure within said space, I vary the size of the central open space, in other words, the radial thickness of the body of liquid. An explosive mixture is admitted intermittently 25 to the central space of the vessel, which is encircled by the liquid so that the incoming liquid causes an increase in the volume of liquid in the chamber, and a corresponding reduction in the volume, and a compression 30 of the explosive mixture. Upon igniting the mixture, the force of the explosion drives the liquid from the chamber with increased energy over that possessed by the liquid when it entered the chamber. The high velocity 35 of the escaping liquid is due primarily to the force of the explosion, but is also due in part to the residual velocity possessed by the liquid and by virtue of which it maintained its movement as an annular body against and 40 along the peripheral wall.

Thus, in carrying out my invention the construction does not embody any moving parts other than the control valves, and the force of the explosion is utilized for imparting increased velocity and kinetic energy to the body of liquid continually moving by kinetic energy rather than by mechanical means.

In order that the admission of liquid may be continuous, there is preferably provided 45 a preliminary air cushioning chamber. The liquid may be continually delivered to this chamber in a generally tangential direction and at such velocity that it forms an annular liquid body around a central air space. It 50 is delivered tangentially from this chamber to the power or working chamber above referred

to. The liquid may be continuously admitted to the preliminary chamber and intermittently delivered to the working chamber, so that the central air will be alternately increased and decreased in size. During the decrease in size the air is compressed and this air pressure aids in the forcing of the liquid into the power or working chamber when the inlet port of the latter is open. 60 65

In order that the delivery of liquid from the apparatus may be continuous, a third chamber may be connected to the outlet of the main or working chamber, and similar in construction to that of the preliminary chamber. This third chamber will thus receive liquid intermittently at high velocity from the working chamber, and deliver it continuously by reason of its velocity, and by reason of the expansion of the air, when the outlet 70 75 port of the main chamber is closed.

The liquid stream delivered from the apparatus may be utilized in any desired manner, for instance, for delivery to an elevated point, or for operating a turbine, or for storage under pressure. If desired the turbine 80 may be incorporated as a part of the apparatus itself.

By means of my invention a stream of liquid may be continuously admitted and continuously delivered and increased energy imparted to it during its movement through the apparatus and without the use of any moving parts other than the valves. 85

In the accompanying drawings I have illustrated certain embodiments of my invention, although it will be obvious that the details illustrated are comparatively unimportant, and that various changes may be made in the construction and arrangements of the 90 95 parts without departing from the spirit or scope of my invention.

In these drawings:

Fig. 1 is a side elevation, partly in vertical section, of a simple type of apparatus, the inlet and outlet valves being removed, but their positions being indicated in dot and dash lines; 100

Fig. 2 is a plan view, partly in horizontal section, of the apparatus shown in Fig. 1; 105

Fig. 3 is a transverse section on the line 3-3 of Fig. 1, the wall of rotating liquid being of reduced or minimum thickness, as for instance, at the end of the power step in the cycle; 110

Fig. 4 is a section similar to Fig. 3, but showing the liquid wall of increased thick-

ness. For instance, as at the beginning of the power step in the cycle;

Fig. 5 is a sectional view of a combined guide and non-return or valve mechanism for 5 the liquid;

Fig. 6 is a view of another form of non-return mechanism with a double flap;

Fig. 7 is a detail of a further form of valve or non-return mechanism;

10 Fig. 7^a is a section on the line 7^a—7^a of Fig. 7;

Fig. 8 is a sectional view of a further guide and valve mechanism;

15 Fig. 9 is a horizontal section of a further form of engine having an air chamber for receiving the liquid from the working chamber;

Fig. 10 is a side elevation of the engine shown in Fig. 9, but on a smaller scale;

20 Fig. 11 is a longitudinal section of a further form of engine having both preliminary and supplemental air chambers;

Fig. 12 is a transverse section on the line 12—12 of Fig. 11;

25 Fig. 13 is a sectional detail of the valve mechanism shown in Fig. 11 and differing somewhat in detail from the valve mechanism shown in Figs. 5 to 8 inclusive;

30 Fig. 14 is a longitudinal section of a further form of engine having a turbine embodied therein; and

Fig. 15 is a transverse section on the line 15—15 of Fig. 14.

In the simple form of construction illustrated in Figs. 1 to 4 inclusive, there is provided a substantially cylindrical vessel 4 having tangentially disposed inlet and outlet passages 8 and 9. These are so disposed that the liquid entering the passage 8 and travelling around the inner surface of the peripheral wall of the vessel, may build up in thickness along the length of the vessel and may escape through the outlet passage 9 with the minimum change of direction. At one end 45 of the vessel there are provided one or more inlet valves 16—17 for the explosive mixture or the components thereof and for scavenging air, and at the opposite end is an exhaust port with a suitable valve. Adjacent to the inlet valves there is provided an igniting means, such, for instance, as a spark plug 7.

The liquid inlet and outlet ports or passages 8 and 9, are provided with suitable non-return valves such as 21 and 22. These 55 are illustrated as of the spring pressed poppet type, and so designed as to offer the minimum resistance as to the flow of liquid and to insure substantially instantaneous operation. As will be apparent any suitable form of 60 non-return valve, automatic or mechanical valve mechanism may be employed. The inlet valves 16 and 17 for the explosive mixture, the exhaust valve 18, and the igniter 7, will, of course, be operated and controlled 65 mechanically in suitably timed relationship,

the same as in any ordinary internal combustion engine, and the details of these parts may follow suitable standard practice.

The operation of the engine as illustrated in Figs. 1 to 4 inclusive, is as follows:

The explosive mixture is admitted through the valve 16 or the valve 17 or partly through both, and the liquid is admitted through the inlet 8. This liquid is delivered by suitable propelling means and at such velocity that due to the action of centrifugal force it follows the peripheral wall of the vessel and builds up an annular wall or body of liquid around the central space 3. As this wall of liquid increases in thickness, the center space 70 decreases and the explosive mixture is thereby compressed to the desired pressure. At the proper time the explosive mixture is ignited, thereby very greatly increasing this pressure, and this increased pressure acting 75 on the substantially cylindrical wall of liquid, forces the liquid out through the outlet port 9 at high velocity. It will be understood that the delivery of liquid through the outlet 9 is due also in part to the residual velocity by 80 virtue of which it was travelling around the central gas space before and after the ignition of the explosive mixture. The spring of the outlet valve 22 is stronger than that of the inlet valve 21 so as to permit the opening of 85 the outlet valve and the delivery of the liquid under this high pressure, but to prevent escape of liquid under low pressure while liquid is being forced into the chamber. When all 90 or a major portion of the liquid has been thus 100 discharged, the exhaust valve 18 is opened thereby relieving the chamber of further gas pressure, the liquid outlet valve 22 closes, a fresh charge of explosive mixture is admitted through the inlet ports 16 or 17 or 105 both, and liquid is delivered to the chamber through the inlet 8 to compress this fresh charge.

If desired, gas may be admitted through the inlet 16 and air through the inlet 17, to 110 form the explosive mixture in the chamber, or one of these may serve merely for the delivery of scavenging air at the end of the power step and before the closing of the exhaust valve 18. One of the valves 16, 17 may 115 serve merely for air and the other for oil or other combustible liquid to make up the charge.

The liquid which is admitted to the chamber at high velocity, will continue to travel 120 around the chamber as an annular body, during the compression of the charge, the explosion and expansion thereof, and the delivery of the liquid. The thickness of this wall of liquid may be substantially as shown in Fig. 125 3, or may be further reduced in thickness when the exhaust valve 18 is opened at the end of the expansion of the exploded charge, and it may be as thick as, or thicker than, as shown in Fig. 4 at the instant of explo- 130

sion. The charge may be admitted during a portion of the compression step as is common in internal combustion engine operation and the timing may be varied to obtain the 5 highest efficiency.

It will be understood that the energy generated by the explosion will be transmitted to the liquid and that thus the liquid will leave the chamber with very materially increased 10 energy over that which it possessed when admitted. It will also be understood that it is essential that the entrance liquid have sufficient energy to cause it to maintain the annular liquid wall during the compression 15 and explosion steps of the process. The working space 3 thus performs a sort of respiratory movement or pulsation, by varying in diameter, and the peripheral wall of the working space is formed by the rotating liquid 20 ring or body. Only the ends of the working space are formed by stationary walls of the chamber, and in these are located the inlet and exhaust ports and the ignition means for the gas.

25 In order to convert the intermittent delivery of the working liquid from the chamber 4 to a substantially uniform delivery for better utilization in a turbine or other apparatus, I may, and preferably do, provide a cushioning device as shown in Figs. 9 and 10. The working chamber shown at the right hand side of Fig. 10 and at the upper part of Fig. 9, may be substantially identical with that shown in Figs. 1 to 4 inclusive, although in 30 the construction illustrated in Figs. 9 and 10 certain of the details are different. The liquid inlet port 8 is disposed at the lower end of the working chamber 4, and the outlet port 9 is disposed at the upper part of said chamber. Instead of using the poppet type 35 of inlet and outlet valves, I have illustrated a series of small flap valves directly in the wall of the working chamber. As shown in Fig. 9 there are a plurality of outlet ports 14 leading to a passage 14^a partly encircling the chamber and leading to the main outlet passage 9. At each of these ports there are small, thin, flexible flaps 48, which permit the outflow of the liquid, with the minimum change 40 of direction, but which instantly close to prevent return flow. The same type of valves 45 may be employed at the lower end for controlling the admission from the port 8 to the working chamber, but these would have the flaps movable inwardly rather than outwardly, as will, of course, be obvious. The outlet 50 valve flaps 48 should be stiffer to offer greater resistance than the inlet valve flaps.

Coupled to the main working unit is a 55 chamber 29, having a central air space 30 which is closed at both ends. The liquid is intermittently delivered through a tangential inlet passage 32, an arcuate passage 32^a and ports 35, past the flap valves 48 to the chamber 29. Due to the high velocity of the liquid, a

liquid body or wall will be formed around the air space and similar to the body of liquid in the main working chamber. The tangential outlet port 33 from the lower end of this air chamber may be permanently opened, and 70 so that there will be a continuous and substantially uniform delivery of liquid through this port. A suitable diffuser 34 may receive the liquid from the passage 33 if the high velocity is to be converted into pressure. 75

During the intermittent high speed delivery of liquid to the chamber 29, the wall of liquid will increase in thickness and air will be compressed in the central space 30. During the interruption of the liquid delivery, 80 that is during the compression step in the main working chamber, the compressed air in the space 30 will expand and maintain the delivery of liquid from the chamber 29. Thus the intermittent delivery from the 85 working chamber is converted into a substantially uniform delivery as the air in the center space 30 is alternately compressed and expanded.

As previously noted the simple type of apparatus shown in Fig. 1, takes in liquid intermittently and delivers it intermittently, while in the construction shown in Fig. 9 the liquid is taken in intermittently, and delivered continuously. Substantially the same type of 95 air chamber used in insuring continuous delivery may be connected to the inlet of the working chamber to permit continuous admission of liquid to the apparatus. 90

A further form of my invention and in 100 which this continuous intake and delivery of liquid is maintained, is shown in Figs. 11, 12 and 13. The liquid is continuously delivered tangentially to inlet chamber 41, and builds up an annular body of liquid around the central space 40. From this the liquid may be delivered approximately tangentially, but at the same time axially through ports 39, between diagonal guides 39^a (see Fig. 13) and past flap valves 48^a to the working chamber. 105 The operation which takes place in this chamber is substantially the same as that which takes place in the main chamber shown in Fig. 1, that is air, combustible gas and scavenging air are delivered at the proper timed intervals through the ports 16 and 17, the charges igniting by the spark plug 7 and the exhaust is delivered through the outlet ports 18, to impart the desired increased energy to the body of liquid circulating in the working chamber. This liquid during the explosion stroke, escapes through ports 32, between guides 32^a and past non-return flap valve 42^a 110 to the air chamber 29. The liquid may be continuously delivered from the air chamber 29, past non-return valves 42^b to the outlet 115 33. In this construction the liquid is continuously admitted to the first air chamber and continuously delivered from the last air chamber. It is intermittently delivered from the 120 125 130

first air chamber to the working chamber, and intermittently delivered from the working chamber to the last air chamber. In all three chambers it is under sufficient velocity to 5 maintain the form of an annular circulating body, and greatly increased energy is imparted to it by the force of the explosions in the working chamber.

In Figs. 14 and 15 there is illustrated an 10 apparatus similar in many respects to that shown in Figs. 11 and 12, except that here the liquid is delivered to the first air chamber 41, past a valve 21 substantially shown in Fig. 2, but is delivered axially and then guided by 15 vanes 23, so that it enters the chamber 41 in a generally tangential direction to form the rotating body of liquid.

At the opposite end instead of being delivered through a single outlet 33 as in Figs. 20 9 and 11, it is directed by guiding vanes 25, similar to vanes 23, to an annular series of 25 adjustable vanes 51, from which it is delivered to a turbine 50. Each of these vanes may be pivoted and the pivot 24 of each is 30 connected to a crank 52 on the outside of the apparatus. The several cranks may be connected to a ring 53 which may be oscillated to vary the angle or direction of the vanes 51. This arrangement of adjustable vanes 35 and the operating mechanism therefor, may be a well known construction, such, for instance, as shown in my prior Patent No. 1,199,361.

Figs. 5 to 8 inclusive merely show the 35 details of non-return flap valves which may be employed in any of the forms above described. In Fig. 5 there are main stationary guides 46, with supplemental guides 47, each having a thin flap 48 of such flexibility that it readily 40 bends over to touch the next flap and prevent return flow of liquid. In Fig. 6 each of the 45 vanes 47 is provided with a double flap 48^c fixed at the rear and having free ends which provide the minimum moving mass and afford very great strength. These flaps automatically 50 adjust themselves to the direction of the flow of the liquid, but due to their elasticity, are able to quickly bend down to closed position.

In Fig. 7^a I have shown a pair of vanes and flaps similar to those shown in Fig. 6, and have shown in solid and dotted lines different positions which the flap may assume.

In Fig. 8 I have shown an arrangement of 55 guides and flaps which are designed to insure a smooth inner surface for the rotating liquid when the latter is not flowing out of the chamber. The chamber 62 communicates with the passage 61 through ports between stationary members 63. Each member has flap 60 which may fold out to the position shown in dotted lines, to permit the outflow of liquid, but has sufficient rigidity to normally occupy the position shown in solid lines to provide 65 a smooth surface or liquid flow around the

wall of the vessel. This construction may be employed separate from and in advance of the non-return valves if the flaps be very flexible, or may constitute the non-return valves if the flaps have sufficient stiffness.

As previously noted the additional energy 70 imparted to the liquid by my improved device, may be utilized directly as kinetic energy in a turbine or other apparatus, or by means of a diffuser the velocity may be converted into pressure, and this pressure stored or utilized in any suitable manner. If the device is to be used for forcing liquid to a high elevation the delivery pipe leading to such elevation may connect directly to the outlet 75 80 of the apparatus.

Having thus described my invention what I claim as new and desire to secure by Letters Patent is:

1. An internal combustion pump for increasing the kinetic energy of a stream of water, including a chamber having a free and unobstructed interior, a cylindrical peripheral wall, a tangentially disposed inlet and a tangentially disposed outlet, whereby 85 a stream of water may be intermittently delivered through said inlet, at such velocity that it forms an annular body of water of varying thickness following said peripheral wall and encircling a central free space, the 90 ends of said space being provided with means for admitting an explosive mixture, means for igniting said mixture, and means for exhausting combustion gases, whereby during 95 admission of liquid to said chamber a combustible charge is compressed in the central space of the chamber and said liquid is delivered at high velocity upon the ignition of said mixture.

2. An internal combustion pump for increasing the kinetic energy of a stream of water, including a chamber, having a free and unobstructed interior, a cylindrical peripheral wall, and tangentially disposed inlets and outlets, the inlet, of said chamber including an 100 arcuate surface of guiding vanes and automatic check valves, said chamber having means for delivering explosive mixture to and exhausting combustion gases from the central portion thereof and means for igniting said mixture, 105 whereby a stream of water may be delivered to said chamber to maintain an annular body of rotating liquid acting to compress an explosive mixture during admission of liquid and increase in the thickness of the annular 110 body and delivered from said body at high velocity upon explosion of said mixture.

3. An internal combustion pump adapted to receive a stream of liquid and deliver the same with increased kinetic energy, including 115 a chamber having a tangentially disposed inlet, provided with a substantially annular series of helically disposed valve controlled passages, said chamber having the central part provided with an inlet for an explosive 120 125 130

- charge, means for igniting said charge and an outlet for combustion gases, the interior of said chamber being free and unobstructed, whereby a stream of liquid may be delivered 5 to and discharged from chamber, and whereby the liquid may be delivered to said chamber at such velocity as will maintain an annular body of rotating liquid encircling a central free space.
- 10 4. The method of increasing the velocity of a stream of water, which includes maintaining an annular body of water around a central space by intermittently delivering a stream of water tangentially to said body at a velocity corresponding to the centrifugal 15 force required to maintain the body in an annular form intermittently delivering an explosive charge to the central space encircled by said body, whereby said charge is compressed during the admission of said stream, 20 igniting said mixture, and delivering a stream of water from said body in a tangential direction under the pressure of the explosion, whereby increased kinetic energy is imparted to the water.

HERMANN FÖTTINGER.
